UNITED STATES PATENT OFFICE

137,830

DESIGN FOR A DISCHARGE UPTAKE FOR STEAM BOILERS

Edward J. Mabrito, Richmond, Calif.

Application July 27, 1943, Serial No. 110,776

Term of patent 14 years

(Cl. D81—25)

To all whom it may concern:

Be it known that I, Edward J. Mabrito, a citizen of the United States and a resident of the city of Richmond and county of Contra Costa, State of California, have invented a new, original, and ornamental Design for a Discharge Uptake for Steam Boilers, of which the following is a specification, reference being had to the accompanying drawing, forming part thereof.

Figure 1 is a perspective view of a discharge uptake for steam boilers showing my new design.

Figure 2 is a perspective view of the side and end opposite that shown in Figure 1.

I claim:

The ornamental design for a discharge uptake for steam boilers, substantially as shown.

EDWARD J. MABRITO.
